Letters Patent No. 92,671, dated July 13, 1869.

IMPROVED STAIR-ROD.

The Schedule referred to in these Letters Patent and making part of the same.

To all whom it may concern:

Be it known that I, H. UHRY, of the city of New York, in the county and State of New York, have made a new and useful invention in Stair-Rods; and I do hereby declare that the following is a full and exact description thereof, reference being had to the accompanying drawings, and to the letters of reference marked thereon.

This invention relates to an improvement on one of my stair-rods, for which I have been allowed a patent, and it is designed to enable the wooden stair-rods to be reversible, and to adapt my pin-fastenings to metal rods.

Figure 1, of my drawings, represents a front view of my improved stair-rod when in place;

Figure 2 is a horizontal section of the same through its centre; and

Figure 3 represents the same view of a metallic stair-rod.

A is a stair-rod, made of wood, metal, or any other material, and of any desired shape, but having, near both of its ends, a hole bored through the thickness thereof, opposite the place where it is intended said rod should be secured to the stair-case.

In the case of a wooden rod, or when the rod is made of a certain thickness, a hole running in the direction of the rod, and bored from both its ends to a certain depth, has to be made to intersect the other holes. This is seen in fig. 2, and marked a.

B is a hollow cap, slipping freely into the holes of

the rod A, but having an outside flange at its base, to prevent it going through the same.

This cap B has two small holes drilled through its opposite sides, to allow of the pin P being passed entirely through the same.

I use for this stair-rod the same screw-eye or drilled screw as for my other pin-fastening stair-rod. This is represented by T.

Now, when the cap B is placed over the screw-eye T, and that the pin P is passed through the holes in the cap B, this cap is retained firmly upon the screw-eye T; and if, before being placed upon the screw-eye T, the cap B is thrust into the hole of the rod A, and while there, is fastened to the screw-eye T, as above stated, it is evident that the rod will be securely fastened also.

Disclaiming a stair-rod made of wood having cavities or holes partly bored through its thickness, and holes in combination with the pin and hook, as described in my patent, No. 86,884, issued February 9, 1869,

What I do claim, and desire to secure by Letters Patent of the United States, is—

The combination of the cap B, pin P, and screw-eye T, with the rod A, arranged and operating in the manner set forth and shown.

H. UHRY. [L. S.]
